CLAIM

The ornamental design for a fluid end stuffing box as shown and described.

DESCRIPTION

FIG. 1 is a rear perspective view of a first example embodiment of a fluid end stuffing box in the environment of a fluid end;

FIG. 2 is a front perspective view of the fluid end stuffing box of FIG. 1;

FIG. 3 is a rear view of the fluid end stuffing box of FIG. 1; FIG. 4 is a front view of the fluid end stuffing box of FIG. 1;

FIG. 5 is a first side view of the fluid end stuffing box of FIG. 1;

FIG. 6 is a second side view of the fluid end stuffing box of FIG. 1;

FIG. 7 is a top view of the fluid end stuffing box of FIG. 1; and,

FIG. 8 is a bottom view of the fluid end stuffing box of FIG. 1.

Any portions shown using dashed lines are for illustrative purposes only and form no part of the claimed design.

1 Claim, 4 Drawing Sheets
